UNITED STATES PATENT OFFICE

ARTHUR B. MODINE, OF RACINE, WISCONSIN, ASSIGNOR TO MODINE MANUFACTURING COMPANY, OF RACINE, WISCONSIN, A CORPORATION OF WISCONSIN

MEANS FOR AND METHOD OF PACKAGING ARTICLES

Application filed November 19, 1926. Serial No. 149,364.

My invention relates to means for and a method of packaging articles and has among its other objects the provision of devices of the kind described which are compact, convenient, durable, efficient and satisfactory for use wherever found applicable.

A particular object of the invention is to provide improved cartons wherein articles may be packaged for shipping purposes and which may be employed to temporarily contain and protect the articles, after the articles are put in use.

Another particular object of the invention is to provide an improved carton for shipping articles, which carton will be so constructed that it may be subsequently modified and utilized to protect the article after the article has been put in use.

Many other objects and advantages of the construction herein shown and described will be obvious to those skilled in the art from the disclosure herein given.

To this end my invention consists in the novel construction, arrangement and combination of parts herein shown and described, and more particularly pointed out in the claims.

In the drawings, wherein like reference characters indicate like or corresponding parts:

Fig. 1 is a perspective view of a carton embodying the invention;

Fig. 2 is a vertical section taken through the improved carton after it has been modified to become a protective covering or housing for a radiator cabinet; and

Fig. 3 is a section taken on substantially the same line as Fig. 2 but showing the carton modified as a housing for a radiator unit.

It is believed that a complete understanding of my improved method will be had from a description of devices with which the improved method is practiced.

Referring for the present to Fig. 1, the reference character 10 designates generally a carton which may be formed of any suitable material but is preferably formed from cardboard, fiberboard, or the equivalent. In the illustrated embodiment of the invention, the carton 10 is particularly adapted to be em-

ployed as a shipping case or carton for radiator units and cabinets of the kind shown and described in my copending application, Serial No. 178,658, filed March 26, 1927. It will be noted that the carton 10 comprises front and rear walls 11 and 12 respectively and side walls 13. The top and bottom sides of the carton are preferably closed by flaps 15 formed integral with the front and rear walls 11 and 12, respectively, and by flaps 16 formed integral with the side walls 13, it being obvious that the flaps 15 and 16 may be folded into the position wherein they are shown in Fig. 1 to enclose an article within the carton. The carton 10 shown in Fig. 1 encloses a radiator cabinet 18 which is shown in dotted lines.

The radiator cabinet 18 is particularly adapted to be used in connection with the radiator unit 20 shown in Fig. 3, the radiator unit being of the type more fully shown and described in my copending application, Serial No. 634,492, filed April 23, 1923. As shown in Figs. 1 and 2, the radiator cabinet 18 is provided with a plurality of legs 22 adapted to rest upon a floor or the like to space the walls of the cabinet therefrom so that air may be drawn into the lower end of the cabinet and then be discharged therefrom through a grille 24 positioned in the upper end of the cabinet. The cabinet 18 is adapted to be positioned over the radiator 20, and it is readily understood that when a heated fluid passes through the radiator unit, the radiator unit will heat the surrounding air and cause a current of air to flow in the manner above described.

It is, of course, understood that the carton 10 protects the cabinet 18 from injury during transit when it is being shipped from the manufacturer to the place where it is to be installed, but as it is one of the objects of this invention to protect the radiator unit and cabinet from injury after they have been installed in the building, it is deemed best to state the advantages from such protection.

It is often desirable to heat a building under construction so as to dry out the plaster, etc., therein. It is also necessary at times to

heat the building because of the workmen. However, it is readily apparent that when the radiator unit and cabinet are so employed they are necessarily subjected to the dirt and dust which accompany building operations and, in practice, it has been found that the radiator cabinets are frequently damaged by the workmen who place their tools thereon or strike the cabinet or unit with pieces of building material.

10 To overcome this danger of injury to the cabinet and the radiator unit, the carton 10 is preferably constructed in such a manner that it may be employed as a temporary cover for the radiator and cabinet. Thus, I preferably indicate by dotted lines 26 and 27, or the equivalent, panels 28 and 29 respectively which should be removed from the carton when it is to serve as a temporary cover for the cabinet or radiator unit. In Figs. 2 and 3, I have shown the panels 28 and 29 removed from the carton to provide upper and lower openings 30 and 31 respectively, the opening 31 being formed adjacent the bottom 25 of the carton so that air may enter therein and pass upwardly through the cabinet and thence to the grille 24 and opening 30. It will be noted that the bottom of the carton is cut therefrom when the carton is employed 30 as a temporary cover. On the front wall 11 of the carton, I preferably print instructions 33 which direct the workmen to modify the carton 10 so that it may be employed as a temporary cover for the cabinet or radiator unit.

35 In Fig. 2, I have shown the carton 10 employed as a temporary cover for a cabinet 18 which has been assembled with a radiator unit 20, and in Fig. 3 I have illustrated the 40 carton 10 employed as a temporary cover for the radiator unit 20 by itself.

In some instances, I may prefer to remove the panels 28 and 29 from the carton before the article is shipped and in other instances, I 45 may prefer to omit the bottom wall also and provide a temporary bottom therefor or enclose the carton in another carton.

Having thus described my invention, it is obvious that various immaterial modifications 50 may be made in the same without departing from the spirit of my invention; hence I do not wish to be understood as limiting myself to the exact form, construction, arrangement and combination of parts herein shown and described or uses mentioned.

55 What I claim as new and desire to secure by Letters Patent is:

1. A combined shipping carton and temporary cover for a radiator having opening outlines depicted on the outside of said carton, one of the outlines being located to correspond with the inlet of a draft passage of said radiator, the other outline being arranged to correspond with the outlet of said 60 draft passage of the radiator, the material 65

of the carton being adapted to be severed at said outlines to thereby provide openings in the carton which respectively communicate with said inlet and outlet of said draft passage of the radiator to thus produce a heat 70 deflecting casing for deflecting heat emanating from the radiator confined in said casing.

2. A combined shipping carton and temporary cover for a radiator, said carton having indicia providing means on the outside 75 of said carton denoting the position of an air inlet of a draft passage for a radiator confined in said carton, the material of the carton being adapted to be severed at said means to thereby provide an air inlet opening in 80 said carton, indicia providing means on the outside of said carton denoting the position of an air outlet which communicates with said air inlet opening of said carton, the material of said carton being adapted to be severed at 85 said last mentioned indicia to provide said carton with an outlet opening and a draft passage through the radiator confined in said carton.

In testimony whereof, I have hereunto 90 signed my name.

ARTHUR B. MODINE.
